CLAIM

The ornamental design for a cart, as shown and described.

DESCRIPTION

FIG. 1 is a front perspective view of my new design for a cart.

FIG. 2 is a left side elevation view; with the right side being a mirror thereof;

FIG. 3 is a front side elevation view of FIG. 1

FIG. 4 is a back side elevation view of FIG. 1.

FIG. 5 is a top plan view of FIG. 1.

FIG. 6 is a bottom plan view of FIG. 1; and,

FIG. 7 is a side elevation view of the cart, with the top shelf its alternate positions, the only difference being the positions of the top shelf, it being understood that all other elements are the same.
